Primary Examiner — Elizabeth J Oswecki*(74) Attorney, Agent, or Firm* — Middleton Reutlinger(57) **CLAIM**

The ornamental design for a mouthpiece, as shown as described.

DESCRIPTION

FIG. 1 is a top, front, right side perspective view of a first embodiment of a mouthpiece showing my new design;

FIG. 2 is a bottom, front, left side perspective view thereof;

FIG. 3 is a top, rear perspective view thereof;

FIG. 4 is a front elevational view thereof;

FIG. 5 is a rear elevational view thereof;

FIG. 6 is a right side elevational view thereof;

FIG. 7 is a left side elevational view thereof;

FIG. 8 is a top plan view thereof;

FIG. 9 is a bottom plan view thereof;

FIG. 10 is a top, front, right side perspective view of a second embodiment of a mouthpiece showing my new design;

FIG. 11 is a bottom, front, left side perspective view thereof;

FIG. 12 is a top, rear perspective view thereof;

FIG. 13 is a front elevational view thereof;

FIG. 14 is a rear elevational view thereof;

FIG. 15 is a right side elevational view thereof;

FIG. 16 is a left side elevational view thereof;

FIG. 17 is a top plan view thereof; and,

FIG. 18 is a bottom plan view thereof.

The broken lines shown in the drawings represent portions of the mouthpiece that form no part of the claimed design.
